United States Patent Office

Des. 212,431
Patented Oct. 15, 1968

212,431

DOLL

Reuben B. Klammer, 245 S. Barrington,
Los Angeles, Calif. 90049

Filed Apr. 14, 1967, Ser. No. 6,693

Term of patent 14 years

(Cl. D34—4)

I claim:

The ornamental design for a doll, substantially as shown.
